United States Patent Office

Des. 183,984
Patented Nov. 25, 1958

183,984

CASKET

Robert C. Volkel, Garden Grove, Calif., assignor of forty percent to Russel F. Tewalt, Garden Grove, and ten percent to Frank G. Volkel, Los Angeles, Calif.

Application November 18, 1957, Serial No. 48,527

Term of patent 14 years

(Cl. D19—1)

Fig. 1.

Fig. 2.

Fig. 3.

Fig. 1 is a top plan view of a casket showing my new design; the base of the casket having the same appearance as the top;

Fig. 2 is an elevation of one side of the casket, the opposite side being identical in appearance; and

Fig. 3 is an elevation of one end of the casket, the opposite end having the same appearance.

I claim:

The ornamental design for a casket, substantially as shown and described.
